Primary Examiner — Wan Laymon(74) *Attorney, Agent, or Firm* — Alston & Bird LLP(57) **CLAIM**

The ornamental design for a valve for vacuum, ejector, or the like, as shown and described.

DESCRIPTION

FIG. 1 is a perspective view of a valve for vacuum, ejector, or the like according to my new design;

FIG. 2 is a right side elevation view thereof;

FIG. 3 is a left side elevation view thereof;

FIG. 4 is a top plan view thereof;

FIG. 5 is a bottom plan view thereto;

FIG. 6 is a rear elevation view thereof; and,

FIG. 7 is a front elevation view thereof.

The broken lines immediately adjacent the shaded areas represent bounds of the claimed design and environment while all other broken lines are directed to environment and are for illustrative purposes only. The broken lines form no part of the claimed design.
